UNITED STATES PATENT OFFICE.

GRACE T. GAREY, OF QUINCY, MASSACHUSETTS, ASSIGNOR TO CHENEY BROTHERS, OF SOUTH MANCHESTER, CONNECTICUT.

DESIGN FOR A TEXTILE FABRIC.

SPECIFICATION forming part of Design No. 22,434, dated May 16, 1893.

Application filed April 8, 1893. Serial No. 469,613. Term of patent 3½ years.

To all whom it may concern:

Be it known that I, GRACE T. GAREY, of Quincy, in the county of Norfolk, State of Massachusetts, have invented and produced a new and original Design for Textile Fabrics, of which the following is a specification, reference being had to the accompanying drawing, forming a part hereof.

The object of my invention is to provide a design that may be wrought into, or printed or similarly displayed upon the surface of a textile fabric to be used as hangings, draperies, or any other suitable and convenient purpose, and such design is produced in appropriate tints and colors.

My design consists in the pictorial representation and arbitrary treatment of the flower known as the flowering cactus, the stems, leaves and flower being depicted in colors on the surface of the fabric in the arrangement as shown in the accompanying drawing which is a repeat of the design.

I claim as my invention—

The design for a textile fabric substantially as herein shown and described.

GRACE T. GAREY.
